SHOE TREE

George R. Harrison, Detroit, Mich.

Application April 13, 1944, Serial No. 530,831

7 Claims. (Cl. 12—128.6)

This invention relates to shoe trees and has for its principal object the provision of a shoe tree of simple and improved construction.

Objects of the invention include the provision of a shoe tree including a front form or part consisting of two relatively laterally movable parts and a rear part or form interconnected thereto by means of an expanding mechanism, the connection between the expanding mechanism and the two halves of the forward part being such as to cause the two halves of the forward part to be expanded within the corresponding portion of a shoe when applied thereto and to permit such halves to adjust themselves in such a manner and to such an extent as to substantially fully and evenly fill the associated portion of the shoe; the provision of a construction as above described in which the connection between the expanding mechanism and the two halves of the forward part of the shoe tree effects a positive lateral expansion of the two halves when pressed home in a shoe; the provision of a construction as above described in which the connection between the forward end of the expanding mechanism and the two halves of the forward part of the shoe tree not only serves to spread the two halves of the forward part but to permit them to swivel independently of one another and with respect to their connection with the expanding mechanism to permit them to automatically adjust themselves to the taper of the forward portion of a shoe to which they are applied; the provision of a construction as above described including means for positively collapsing the two halves of the forward part of the shoe tree in withdrawing the shoe tree from a shoe; the provision of a construction as above described in which the connection between the expanding mechanism and the two halves of the forward part of the shoe tree includes a ball end on the expanding mechanism engaged in tapered grooves in the two halves; the provision of a construction as above described in which the connection between the forward end of the expanding mechanism and the two halves of the forward part of the shoe tree further includes a pin projecting laterally through the ball end of the expanding mechanism, the pin in turn having ball ends at its opposite end in turn slidably and preferably rotatably received in bores in the two halves arranged at an angle to the longitudinal center line of such forward part; the provision of a shoe tree of the general character above described including a simple and novel form of means for maintaining the two halves of the for-

ward part of the shoe tree against relatively longitudinal displacement with respect to each other; and the provision of a shoe tree including forward and rearward parts interconnected by means of a toggle mechanism which has a novel form of connection with the rearward of such parts.

The above being among the objects of the present invention the same consists in certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Fig. 1 is a partially broken, partially sectioned plan view of my improved shoe tree;

20 Fig. 2 is a vertical sectional view taken transversely of the shoe tree shown in Fig. 1 as on the line 2—2 thereof;

Fig. 3 is a transverse vertical sectional view taken on the line 3—3 of Fig. 1;

25 Fig. 4 is a partially broken, partially sectioned side elevational view of the shoe tree shown in Fig. 1, illustrating it in operative expanded relation with respect to a shoe a portion of which is indicated by dot and dash lines;

30 Fig. 5 is a view similar to Fig. 4 but illustrating the shoe tree in collapsed position;

Fig. 6 is a plan view of the forward portion of the shoe tree shown in the preceding figures and illustrating one extreme position of angular adjustment of the two halves thereof; and,

35 Fig. 7 is a view similar to Fig. 6 but illustrating the opposite extreme position of angular adjustment of the two halves thereof.

Referring to the drawings it will be noted that 40 the shoe tree of the present invention includes a front or forward portion indicated generally at 10, a rear portion indicated generally at 12 and an interconnecting expanding mechanism which may be of any conventional or desirable type 45 but which preferably consists of a toggle link mechanism as shown and indicated generally at 14. The front portion 10 is split vertically and longitudinally thereof into two halves 10a and 10b, respectively, the two halves cooperating to 50 provide a form of approximately the interior shape of that portion of a shoe in which the tree is intended to be received. The portion 12 is generally circular in cross-sectional configuration and is of more or less plug-like or knob-like 55 shape, its rounded rear end adapted to be more

or less loosely received within the rear portion of a shoe in a conventional manner. The toggle mechanism 14 comprises a forward link 16 which is connected to the forward part 10 in a manner which will hereinafter be described in detail, a rear link or member 18 the forward end of which is bifurcated and receives the rear end of the link 16 therein, and a handle portion 20 having a bifurcated lower end in which the forward end of the link 18 is received, a horizontally extending pivot pin 22 extending through the bifurcated ends of the handle portion 20 and link 18, and the rear end of the link 16, thereby to pivotally connect all of these parts together.

The member 18 is exteriorly threaded and its rear end is received in a complementarily threaded bore in the rear part 12 so that the position of the rear part 12 may be adjusted along the length of the member 18 in order to enable the shoe tree to be adjusted in length to fit different lengths of shoes. Preferably a lock nut 24 threaded on the member 18 is provided for engagement with the forward end of the rear part 12 so as to enable it to be releasably locked in adjusted position upon the member 18.

In the broader aspects of the invention it will be appreciated that the shoe tree illustrated is adapted to be formed in whole or in part from any suitable material such as metal, plastic, or other moldable composition, or of wood, and regardless of what material the rear part 12 and member 18 are formed from broadly it makes no difference how the threaded connection between them is provided. However, and in accordance with a narrower phase of the present invention, where the rear part 12 is formed of wood then it is desirable that it be provided with a metallic nut part for cooperation with the threads of the part 18. In such case, in accordance with one phase of the present invention the rear part 12 is provided with a blind bore 30 which, as best brought out in Fig. 4, extends from the forward end thereof and centrally thereof to a position adjacent but short of the rounded rear end thereof, and in the forward portion of this bore is fixed a metallic nut 32 having a threaded bore operatively receiving the threads of the member 18 therein. For the purpose of simplicity and economy the nut 32 is preferably formed in the following manner. The forward portion of the bore 30 is slightly enlarged as at 34. The part 12 is positioned with its axis vertical and its open end upwardly. Then a threaded metal part of the same diameter and pitch of threads as the part 18 is projected downwardly into the bore 30 and held concentrically therein. Then molten lead or other suitable metal is poured into the enlarged upper end 34 of the bore 30 until the portion 34 is full and has solidified whereupon the threaded member is removed thereby providing the nut 32. The enlarged end 34 may be made irregular in cross-sectional configuration if desired but ordinarily the molten metal will burn sufficiently into the wood of the member 12 to lock the nut against relative movement with respect thereto without resorting to such expedient.

The two halves 10a and 10b of the forward part 10 are maintained against relative longitudinal movement with respect to each other but without unduly restricting relative lateral movement between them in the following manner. In one of the opposing faces of the two halves 10a and 10b, shown as the half 10b and adjacent the forward end thereof, a blind bore 40 is provided opening

into such face between the upper and lower edges thereof adapted to slidably receive a pin fixed in the other of said halves. The bore 40 is of large enough diameter to freely receive the head 42 of a nail 44 therein which nail provides such pin, the nail 44 being driven into the opposite half, shown as the half 10a, in concentric relation with respect to the bore 40 when the halves 10a and 10b are in flat contacting relation with respect to each other. The nail 44 is preferably driven into the half 10a a sufficient distance so that when the two halves are urged toward flat contacting relation with respect to each other the head 42 thereof will not bottom in the bore 40 to such an extent as to hold the forward ends of the parts 10a and 10b laterally away from each other, but it is preferably located adjacent the blind end of the bore 40 under such conditions, as shown in Fig. 1. The open end of the bore 40 is closed by a collar member 46 which is preferably secured against movement therein by means of a press fit, and through which the body of the nail 44 freely projects to such an extent that the two halves 10a and 10b may be angularly arranged with respect to each other and with respect to the longitudinal center line without binding of the nail in the bore of the collar 46. It will be observed that not only does the described construction maintain the two halves 10a and 10b against substantial relative longitudinal displacement with respect to each other, but it permits them to move freely laterally with respect to each other within the limits of movement of the head 42 of the nail 44 in the bore 40, as well as to permit relative angular movement between the halves 10a and 10b as described.

The connection between the forward end of the toggle mechanism 14 and the forward part 10 constitutes the important feature of the present invention and is as follows. The forward end of the link 16 is provided with a relatively large spherical head or ball 50. As best brought out in Fig. 1 the ball 50 is received between cooperating grooves 52a and 52b formed in the opposed faces of the halves 10a and 10b, respectively, intermediate the ends of the latter. The grooves 52a and 52b are identical to each other and consequently a description of one will serve as a description of both. The groove 52a as brought out in Fig. 1 is partially circular in transverse section, such section being taken in a plane perpendicular to its outer, or upper, edge as viewed in Fig. 1, and the radius of such section is substantially the same as the radius of the ball 50. Such outer edge as viewed in Fig. 1 extends at an angle to the inner face of the member 10a, converging toward such face in a forwardly direction. Its character may be best described by its preferred method of forming which consists in taking a drill of the same diameter as the ball 50 and drilling into the inner face of the half 10a in a direction parallel with the outer edge of the groove 52a as viewed in Fig. 1 until the point of the drill has become imbedded in the half 10a for a distance slightly exceeding its diameter. The ball 50 will, therefore, fit the grooves 52a and 52b in any position along the length thereof. The grooves 52a and 52b converging toward each other in a forwardly direction, it will be appreciated that if the forward part 10 is maintained against forward movement and force is applied to the link 16 to force the ball end 50 thereof forwardly, such ball end in bearing against the walls of the grooves 52a and 52b will cause the halves 10a and 10b to be separated from one another, in accordance

with the disclosure in Fig. 6, for instance, where the forward ends of the halves 10a and 10b are held against separation.

The above described connection between the ball end 50 of the link 16 and the halves 10a and 10b of the front part 10 is a universal connection as will be appreciated so that the halves 10a and 10b may, if otherwise unrestricted, freely swivel about the axis of the ball end 50 with respect to both the ball end 50 and with respect to each other. However, due to the connection between the two halves 10a and 10b provided by the nail 44, this swiveling action between the halves 10a and 10b is restricted to a single plane. The two halves 10a and 10b, in other words the forward part 10, may, however, swivel as a unit in an upwardly and downwardly direction about the ball end 50 by reason of the fact that the opposed faces of the halves 10a and 10b are cut away as at 54 between the rear ends of the halves 10a and 10b and the grooves 52a and 52b to admit the body of the link 16 and this groove is vertically extended to permit the link 16 to swing upwardly and downwardly with respect to the front part 10, this being necessary to collapse the toggle mechanism 14 to the position, for instance, shown in Fig. 5 to permit the shoe tree to be conveniently introduced into and removed from a shoe.

The swiveling action between the ball 50 and the two halves 10a and 10b of the forward part 10, coupled with the fact that the point of engagement between the ball 50 and the two halves 10a and 10b is intermediate the opposite ends of such halves is of material important for the reason that it thereby renders the two halves so adjustable as to enable them to automatically adjust themselves into firm expanded condition with respect to shoes of varying interior widths as well as to varying tapers in their forward portions.

For instance, where the shoe tree is introduced into a shoe having a relatively narrow toe which the forward end of the front part 10 may substantially fit without expansion, then upon operating the toggle mechanism from the position illustrated in Fig. 5 to the position illustrated in Fig. 4, the ball 50 in moving forward in the grooves 52a and 52b will simply serve to expand the rear portion of the halves 10a and 10b away from each other, as brought out in Fig. 6, until the rear portion of such halves are in firm and engaging relationship with respect to the complementary portions of the shoe.

On the other hand, where the shoe tree is introduced into a shoe having a relatively wide toe and is so shaped as to prevent material expansion or separation of the rear ends of the halves 10a and 10b, the front part 10 of the shoe tree in being forced into position and because of the resistance to expansion of the rear ends of the halves 10a and 10b, will expand somewhat in the manner illustrated in Fig. 7, that is, the forward ends of the halves 10a and 10b will separate from one another until they fill the toe portion of the shoe, as will the rear portions of the halves 10a and 10b, but the movement of the latter in such case will be materially less than the former. On the other hand it will be obvious that the halves 10a and 10b may move equally away from each other or to any angular position with respect to each other either in forwardly or rearwardly converging relation as may be required under the circumstances in order that substantially their full length will be pressed outwardly into firm engagement with the interior surfaces of

the corresponding portion of the shoe in which they are received. It will be appreciated that under such circumstances the force with which the two halves 10a and 10b are forced outwardly into contacting relationship with respect to the interior surfaces of the shoe will be a firm and positive pressure depending entirely upon the force with which the front part 10 is separated from the rear part 12 by means of the toggle mechanism 14 and will not be dependent upon any springs or the like as has heretofore been suggested.

The construction thus far described provides a positive means whereby the two halves of the forward part of the shoe tree may be positively forced apart in order to make them conform to a variety of various sizes and shapes of shoes in which they may be received. It is, of course, desirable to provide some means for positively collapsing the two halves 10 when it is desired to remove the shoe tree from a shoe and to provide some means to prevent inadvertent disengagement of the toggle mechanism 14 from the front part 10. These two features are taken care of simultaneously in accordance with the present invention in the following manner.

A transversely extending pin 60 is projected diametrically through the ball end 50 and is freely axially slidably and preferably freely rotatably received therein. The opposite ends of the pin 60 extend beyond the surface of the ball 50 and are each provided with a ball end 62 thereon in outwardly spaced relation with respect to the surface of the ball 50. It will be noted from an inspection of Fig. 2 that the central portion of the pin 60 which is received within the ball 50 is of substantially no smaller diameter than the balls 62, the pin 60 being reduced in diameter between its central portion and the balls 62. This is done for assembly reasons as in such case the balls 62 may be integral with the pin 60 and still be assembled to the ball 50. The balls 62 are each relatively closely but slidably received in a cylindrical opening 64 formed in the corresponding half 10a or 10b in outwardly spaced but parallel relation with respect to the axis of the corresponding groove 52a and 52b. Each groove 64 communicates with its corresponding groove 52a or 52b through a central slot 66 extending between them and in which the adjacent reduced diameter end portion of the pin 60 is slidably and rotatably received, the slot 66 being of less width than the diameter of the ball 62 so that the balls 62 are confined in their corresponding bores or openings 64. Thus, whenever ball 50 is withdrawn rearwardly within the cooperating grooves 52a and 52b from a position in which the halves 10a and 10b of the front part 10 are expanded away from each other, the balls 62 in engaging the inner walls of their respective bores or openings 64 act to maintain the walls of the grooves 52a and 52b in approximate contact with the ball 50 and consequently act to draw the two halves 10a and 10b toward each other. The pin 60 and the balls 62 do not limit the relative separating or swiveling action between the two halves 10a and 10b for the reason that the pin 60 is axially slideable in the ball 50 and, therefore, permits relative and unequal shifting of either half 10a or 10b with respect to the center line of the device or with respect to each other. The pin 60 is preferably rotatable in the ball 50, as described, so as to reduce the friction of its engagement with the walls of the

slots 66, and the engagement of the balls 62 with the walls of the openings 64.

Furthermore, in view of the fact that the balls 62 are confined in the bores or openings 64, they serve through the pin 60 as a means for preventing inadvertent disconnection of the toggle link 16 with the front part 10. This latter portion of the described construction, therefore, provides a dual function in that not only does it provide a positive means for collapsing the two halves 10a and 10b in withdrawing the shoe tree from a shoe, but additionally it maintains the assembly of the links 16 and the halves 10a and 10b.

In assembling the forward part of the shoe tree thus described, in manufacture, the pin 60 with the balls 62 thereon is first projected through the ball 50. The nail 44 with the collar 46 thereon is driven into its corresponding half 10a, the balls 62 are introduced into their respective bores 64 at the forward ends thereof and the two halves 10a and 10b are then moved forwardly with the balls 52 riding back in their respective bores or openings 64, the forward ends of the halves 10a and 10b being separated from one another at this time. The head 42 of the nail 44 is then introduced into the bore 40, the collar 46 is guided into the outer end of the bore 40 and the two halves 10a and 10b are then pressed toward one another to force the collar 46 into its final position, whereupon the assembly of the forward end of the shoe tree is completed.

Having thus described my invention, what I claim by Letters Patent is:

1. In a shoe tree of the class wherein there is a longitudinally split front part forming two halves and a rear part, and means are provided connecting said parts and cooperating therewith to control the spacing of said parts, the combination with said front part and means, of a head on the forward end of said means, said halves of said front part being formed to provide opposed grooves extending longitudinally thereof in forwardly converging relation on either side of the line of split between them and receiving said head therein for swiveling movement with respect to said halves, and means cooperating between said halves tending to maintain said head in contact with the walls of said grooves.

2. In a shoe tree of the class wherein there is a longitudinally split front part forming two halves and a rear part, and means are provided connecting said parts and cooperating therewith to control the spacing of said parts, the combination with said front part and means, of a ball formed on the forward end of said means, said halves of said front part being formed to provide opposed grooves extending longitudinally thereof at an angle to the plane of said split and receiving said ball therein, and means cooperating between said halves tending to positively maintain said ball in contact with the walls of said groove during contraction of said halves from expanded condition.

3. In a shoe tree of the class wherein there is a longitudinally split front part forming two halves and a rear part, and means are provided connecting said parts and cooperating therewith to control the spacing of said parts, the combination with said front part and means, of a ball formed on the forward end of said means, said halves of said front part being formed to provide opposed grooves of partially circular section extending longitudinally thereof in forwardly converging relation at an angle to the plane of

said split and receiving said ball therein, the radius of the sectional curvature of said grooves being substantially equal to the radius of curvature of said ball, and means cooperating between said halves tending to positively maintain said ball in contact with the walls of said groove during contraction of said halves from expanded condition.

4. In a shoe tree of the class wherein there is a longitudinally split front part forming two halves and a rear part, and means are provided connecting said parts and cooperating therewith to control the spacing of said parts, the combination with said front part and means, of a head on the forward end of said means, said halves of said front part being formed to provide opposed grooves extending longitudinally thereof in forwardly converging relation on either side of the line of split between them and receiving said head therein for swiveling movement with respect to said halves, and means cooperating between said halves tending to maintain said head in contact with the walls of said grooves comprising a member projecting laterally through and beyond the laterally outer surfaces of said head, a head on each outer end of said member, the heads of said member being confined in their respective halves for slidable movement with respect thereto in a direction parallel with respect to the laterally outer edges of the corresponding said grooves.

5. In a shoe tree of the class wherein there is a longitudinally split front part forming two halves and a rear part, and means are provided connecting said parts and cooperating therewith to control the spacing of said parts, the combination with said front part and means, of a ball formed on the forward end of said means, said halves of said front part being formed to provide opposed grooves extending longitudinally thereof at an angle to the plane of said split and receiving said ball therein, and means cooperating between said halves tending to maintain said ball in contact with the walls of said groove comprising a pin projecting through said ball transversely of said plane of split and longitudinally slidably in said ball, a ball formed on each end of said member, and each of said halves being provided with an opening arranged in parallelism with the axis of said groove therein in laterally outwardly spaced relation with respect to said groove, each said opening having a restricted slotted communication with its corresponding said groove, the balls on said members being received in the corresponding of said openings and said members slidably projecting through said slots communicating said openings and said grooves.

6. In a shoe tree of the class wherein there is a longitudinally split front part forming two halves and a rear part, and means are provided connecting said parts and cooperating therewith to control the spacing of said parts, the combination with said front part and means, of a head on the forward end of said means, said halves of said front part being formed to provide opposed grooves extending longitudinally thereof in forwardly converging relation on either side of the line of split between them and receiving said head therein for swiveling movement with respect to said halves, means cooperating between said halves tending to maintain said head in contact with the walls of said grooves, and means cooperating between said halves maintaining them against substantial

longitudinal displacement with respect to each other comprising pin means fixed with respect to one of said halves and projecting perpendicularly with respect to the plane of said split between said halves and longitudinally slidably received in the other of said halves.

7. In a shoe tree of the class wherein there is a longitudinally split front part forming two halves and a rear part, and means are provided connecting said parts and cooperating therewith to control the spacing of said parts, the combination with said front part and means, of a head on the forward end of said means, said halves of said front part being formed to provide opposed grooves extending longitudinally thereof in forwardly converging relation on either side of the line of split between them and receiving said head therein for swiveling movement with

respect to said halves, means cooperating between said halves tending to maintain said head in contact with the walls of said grooves, means cooperating between said halves maintaining them against substantial longitudinal displacement with respect to each other comprising pin means fixed with respect to one of said halves and projecting perpendicularly with respect to the plane of said split between said halves, the other of said halves having a bore opening into that face thereof opposed to said one of said halves and perpendicular to said plane of split, said pin being slidably received in said bore, a head on said pin within said bore, and a collar surrounding said pin in the open end of said bore cooperable with said head to prevent inadvertent withdrawal of said pin from said bore.

GEORGE R. HARRISON.
